UNITED STATES PATENT OFFICE

ERVIN G. BAILEY, OF CLEVELAND HEIGHTS, OHIO, ASSIGNOR, BY MESNE ASSIGNMENTS,
TO FULLER LEHIGH COMPANY, A CORPORATION OF DELAWARE

APPARATUS FOR FEEDING AND METERING PULVERULENT MATERIAL

Application filed April 24, 1924. Serial No. 708,821.

This invention relates to an apparatus for feeding pulverized material, especially adapted for feeding pulverized coal either directly to a furnace in which it is used for fuel, or to a producer by which it is converted into a fuel gas, although not limited to such use and the invention also embraces within its scope a new method of supplying powdered coal to furnaces in proper condition for efficient combustion.

In the use of pulverized coal as a fuel it has been found difficult to obtain uniformity of feed to the furnace, due in part to the condition of the material in the bin or receptacle from which it is taken, and in part to the mechanical nature of the devices employed for effecting the feed.

In accordance with the present invention the pulverized material coming from the bin or receptacle is first acted upon by a preparing or conditioning appliance which mechanically breaks up any lumps or aggregation of particles coming to it and introduces air in such a manner that the particles remain separated and in fluffy condition, the voids being filled with air, so that the material leaving this conditioning appliance and being delivered therefrom by gravitation accumulates in a mass or column of substantially uniform density, with the solid particles lightly contacting with, and supported upon, one another, as distinguished from floating in suspension, but having the voids relatively large and freshly filled with air, so that the particles do not adhere in groups or form lumps of a greater density than the desired or proper density for the accumulated mass.

The material thus prepared or conditioned by being aerated and brought to the desired substantially uniform density, is delivered by a feeding device, which may be, and as herein shown, also is, a measuring device, into a duct through which it is carried by a current of air to the desired final delivery point for the powdered material.

By reason of the aerated and uniform condition of the pulverized material coming to the feed wheel the individual particles are suspended and substantially uniformly dis-

tributed in the air current, which should have sufficient velocity to prevent the settling of the particles in their passage through the duct to the point of final delivering.

Fig. 1 is a general view in elevation of a complete apparatus for delivering pulverized coal with the particles suspended in the air current, said apparatus embodying the appliances for preparing and feeding the pulverized material forming the subject of this invention.

Fig. 2 is a vertical longitudinal section of the principal portion of the apparatus for preparing and feeding the pulverized material, and

Figs. 3, 4, 5 and 6, horizontal sectional views on lines X—3, X—4, X—5, X—6, of Fig. 2, respectively.

Referring to Fig. 1, the bin, or supply receptacle, in which the pulverized material to be delivered is contained, is shown at 2, being vertically over the preparing and feeding appliances, shown collectively at 3 in said figure, by which the pulverized material is fed into the duct, or pipe, 4, leading to the gas producer, furnace, or other desired delivery point, the current or blast of air by which the pulverized material is carried through the duct, 4, being supplied from the pipe or duct, 5, through which air is forced by a blower, 6, operated by a suitable motor, 7, there being, as shown in this instance, belts, 8 and 9, between the motor and blower, and between the motor and the preparing feeding appliances, by which these components of the apparatus may be actuated at the proper speed according to the requirements at any time existing.

Referring now to Fig. 2, which shows the construction of the preparing and feeding mechanism located below the bin, 2, and receiving the pulverized material therefrom by gravitation, said material passes down through the connecting passage, 20, into a chamber containing an agitator or distributor, 21, composed of blades or wings rotated in said chamber above the preparing mechanism, the active component of which

is the rotating wheel, 30, by which the material coming from the bin is loosened, has any accumulations or lumps broken up, and is aerated so that when the particles have again settled into contact with one another the voids are large and freshly filled with air, and adjacent or contacting particles, are not liable to adhere to one another to form lumps again.

From said preparing appliances, the detailed construction of which will be herein-after described, the material descends by gravity into an intermediate settling chamber or receiver, 40, containing a rotating agitator and distributor, 41, similar in character to that in the upper chamber, and from this lower or accumulating chamber the material is delivered at the desired rate by the feeding device proper, shown as a wheel or 10 rotating component, 50, which, as shown in this instance, also serves in connection with other mechanism (shown at 10 Figs. 1 and 2) as a meter for keeping the volumetric measure of the amount delivered, which, 15 owing to the substantially uniform density of said material, also serves as a meter of the weight of solid material delivered by the apparatus while in operation.

The material is delivered by the feeding device, 50, the construction of which will be herein-after described, at 51, into a descending passage, 60, containing a baffle plate, 61, which tends to flatten the falling stream, said material continuing to fall by gravitation over a second baffle plate, 62, the lower edge of which extends into the air-duct between the supply portion, 5, and delivery portion, 4, (see Fig. 1) so as to form a nozzle at 63, where the increased velocity 20 of the air current thoroughly distributes the particles throughout the current flowing through the delivery tube, 4, in which they remain in suspension during the passage to the gas producer, furnace, or final 25 delivery point at which the mixture of air and pulverized fuel is converted or consumed.

The lower baffle plate, 62, is fixed at its upper edge, 64, and has sufficient flexibility to admit of adjustment by an adjusting bolt or link, 65, connected with its lower end and provided with external head, 66, for adjustment, to vary the area of the nozzle at 63, as may be found necessary or desirable.

Referring now to the construction of the preparing or preliminary conditioning device, or separating and aerating appliance, best shown in Figs. 3 and 4, and in the upper portion of Fig. 2, the active component of said aerating appliance, as before stated, in this instance is a wheel, 30, having around its periphery fingers or teeth, 31, thus forming spaces or pockets 35 around the periphery between the teeth

which, so far as the wheel itself is concerned, would be open at top and bottom, but closed or completed on three sides by the sides of the teeth and portion of the wheel periphery between them, and on the 70 fourth side by the wall of the chamber in which the wheel rotates, or a band or annulus which lines the wall at this point.

Cooperating with said rotating component, 30, are two plates, 32 and 33, one above 75 and the other below the said wheel, and each made in the form of an annulus having a flange, 34, lying just within the main outer wall of the apparatus, the flanges of the two plates meeting and just surrounding the outer ends of the pocket forming teeth, 31, of the wheel.

Each plate extends inwardly from the periphery of the wheel a distance about equal to the length of the pocket forming teeth, the upper plate a little greater distance and the lower plate a little less, as clearly appears in Fig. 2, and each plate has recesses or apertures about equal in size to, or somewhat larger than the pockets 90 between the teeth of the wheel, so that if the wheel were standing still in the proper position the upper plate would cover certain pockets or portions of pockets in the wheel and leave the intermediate pockets, 95 or portions of pockets, uncovered or open to the supply chamber above, so that the pulverized material would fall by gravity into the uncovered pockets but would remain supported by the upper plate in the 100 space between said uncovered pockets.

The lower plate is of similar construction but the open spaces in the lower plate lie beneath the non-recessed portion of the upper plate, so that with the wheel standing, as above assumed, the lower plate would cover the bottoms of the pockets, or portions of pockets, left uncovered by the upper plate and thus receive and support the material permitted to fall through the 110 upper plate into the pocket or space in the wheel.

When the wheel is rotating the teeth or pockets travel between the upper and lower plates and the pocket which is closed at the 115 top by the upper plate is then passing over a space or a recess in the lower plate, so that the material contained in said pocket can fall into the space or receiving chamber below, said pocket at this time being 120 covered by the upper plate so that no material enters it where thus discharging into the chamber below.

The feeding or forwarding action of the material from the chamber above to the 125 chamber below the wheel will be readily understood, the pockets of the wheel receiving the material from above as they pass under the spaces or recesses in the upper plate, and discharging into the receiving 130

chamber, 40, below as they pass over the spaces or recesses in the lower plate, and it will be recognized that the movement of the teeth of the wheel past the edges of the recesses in the plates will have a mechanical tendency to break up any lumps or aggregations of particles formed by the adherence together of the particles of material.

10 In addition to, and more important than, the mechanical effect of the teeth and plates in breaking up or reducing the lumps, is the separating and aerating effect which will now be described.

15 As the apparatus is all tightly closed except where open to the air at the top, and delivers into air at approximately atmospheric pressure where the air current takes it, the pulverized material when falling from a 20 pocket into the space or receiving chamber below will displace air which will enter the pocket substantially to the extent that said pocket is emptied of the aerated or loosely piled pulverized material falling from it, 25 and such air coming up into the pocket from below must be displaced by the pulverized material entering from above. The wheel carries the air around with it, and the air thus encounters somewhat forcibly the powdered material coming down from above, 30 with the result that the air is blown into the said entering material with more or less eddying or churning effect and thoroughly loosens and separates the particles, so that 35 they remain in suspension in the pocket or settle into the pocket in a light aerated condition, with each particle practically separated from all its neighbors by the air, thus assuring the maximum of air filled voids 40 between the particles when settled and resting as a column or pile under the action of gravity.

This aerating action gives the material delivered from it a light, fluffy character, as 45 contrasted with the more dense and lumpy condition of the material compacted by gravity in the bin from which it is taken, and I have consequently called the active component a fluffer wheel and the upper and lower 50 plates which cooperate therewith to effect the aeration and produce the fluffy condition, the upper and lower fluffer plates.

The light, fluffy aerated material settles 55 into the receiving chamber, 40, below the fluffer wheel and is delivered therefrom by the discharge wheel, or feed wheel proper, 50, which is similar in construction to the fluffer wheel. Said discharge wheel, 50, has peripheral teeth, 52, the spaces between 60 which form pockets similar to those in the fluffer wheel. All but a relatively small part of said pockets remain uncovered or open to the space above, so that they rapidly fill with the material delivered into the intermediate chamber from the fluffer wheel,

the filling of the pockets being facilitated by the action of the agitator, 41 (see Fig. 4).

The pocketed periphery of said discharge wheel lies directly above a horizontal partition, 53, forming substantially the bottom 70 of the portion of the apparatus containing the fluffing and feeding appliances thus far described, and said horizontal bottom portion is provided with a port or opening, 51, (see Fig. 6 and dotted lines Fig. 5), over 75 the delivery passage, 60, through which the material falls by gravitation from the pockets into said delivery passage as the pockets successively pass over said port, 51, in the rotation of the wheel.

Said port, 51, is made of somewhat irregular shape, as shown in Fig. 6, being narrow and located towards the outer periphery of the wheel at the point where the pockets first come over the port in the 80 rotation of the wheel and gradually widening to the full width of the pockets, with the result that the contents of the pocket are gradually and uniformly discharged into the outlet passage, 60, instead of being dumped in a mass as the pocket passes over the port.

An apron or closure, 54, is provided lying over the portion of the periphery of the feed wheel which is above the discharge 95 port, 51, said apron thus closing the pockets at the top and supporting the material above them at the point where they are passing the discharge port, 51, and delivering the material from the pockets therethrough. 100 Said apron contributes to the uniform filling and packing of the material in the pockets as they enter beneath the apron before coming into communication with the discharge port, 51. Said apron is of sufficient size or extent to cover all pockets which have any portion in communication with the discharge port, 51.

While it is immaterial, so far as the invention is concerned, what means or mechanism may be used for actuating the various moving parts hereinbefore described, the construction of the actuating mechanism as herein shown is as follows:

The fluffer wheel, 30, feed wheel, 50, and 110 distributors, 21, and 41, are all actuated by a main vertical shaft, 70, having connected thereto a worm wheel, 71, meshing with and adapted to be actuated by a worm, 72, driven by the shaft, 73, (see Fig. 1) at the desired speed, which may be varied automatically by any suitable regulating mechanism, or otherwise, according to the requirements, or rate of delivery of the pulverized material 120 desired.

Said worm gear and worm wheel are enclosed in a tight casing having a removable cover, 74, and may run in a bath of oil contained in the lower part of the said casing, 130

which also serves to lubricate the bearing, 75, for the lower portion of the shaft, 70.

Above the driving gearing and oil reservoir the shaft extends through a bushing or bearing, 76, provided with suitable packing, 77, at its upper end above the bottom, 53, of the chamber, 40, and below the feed wheel, 50, which discharges the material from said chamber, the driving mechanism and bearings being thus protected from entrance of the powdered material.

The feed wheel, 50, is loosely fitted upon the shaft, 70, above the said packing, 77, and the lower distributor, 41, has a long sleeve-like hub also loosely fitted on the shaft and resting upon the hub of the feed wheel, 50.

The fluffer wheel, 31, also has its hub loose upon the shaft, and the upper distributor, 21, has a sleeve-like hub also loose upon the shaft and resting upon the hub of the fluffer wheel.

The several hubs of the feed wheel, fluffer wheel, and distributors are interlocked for rotary movement by tongues or clutch teeth from the end of one hub entering recesses in the end of the adjacent hub, as shown in dotted line in Fig. 2, so that all of these components necessarily rotate in unison, and the power is transmitted from the shaft, 70, to them by a comparatively weak key or shear pin, 78, (see Figs. 2 and 3) which connects the shaft, 70, with the sleeve-like hub of the upper distributor, 21, and affords an adequately strong connection for driving all of the parts under normal conditions, but would be sheared off and release the driving shaft without breaking any of the parts, in case a solid piece were caught between the fluffer wheel and plates or between the feed wheel and adjacent parts, or in case there should be any other accidental obstruction at any point to the movement of the moving parts.

Suitable hand openings and removable cover plates are provided, as shown, where required, to afford access to the internal components to the apparatus.

The lower end of the feed wheel shaft, 70, is shown as connected at 80, with a flexible shaft, 81, leading to a counting mechanism, 82, of any suitable or usual construction, so that the apparatus while serving to feed the material in proper condition to be thoroughly and uniformly distributed in the air current by which it is conveyed to the final delivery point, also serves as a meter for keeping account of the amount of material delivered.

The mechanical operation is apparent from the foregoing description of the construction.

Power being applied to the blower, 6, the current of air is forced through the pipes, 5, 4, issuing as a flat jet from the nozzle, 63,

with a relatively high velocity and there encountering and entraining the particles of pulverized material falling from the preparing and feeding mechanism through the discharge passage, 60, and carrying the said particles suspended in a current of air through the portion of the duct beyond the nozzle and thence through the delivery pipe, 4, without swirling, and with uniform velocity, sufficient to prevent any settling of the particles to the bottom of the tube.

Power applied to the shaft, 73, causes the vertical shaft, 70, to rotate at a desired speed and rotates the several rotating elements supported on that shaft which act upon the material as it descends through or past them as has been described.

The relative arrangement of the fluffer plates and fluffer wheel cause the downward movement of material to be intermittent at this point, although taken as a whole there is a substantially constant downward movement of material above and below the wheel, and it will be recognized that substantially the entire contents of the wheel pockets will be, or may be, discharged in a rotary movement about equal to the space occupied by one recess and one intervening portion of the cover plate, so that in the proportion shown in Fig. 3 the entire contents of the wheel pockets will be discharged practically twice at each rotation of the wheel.

In the case of the feed wheel, 50, however, inasmuch as the pockets are emptied consecutively one at a time, the entire contents of the pockets will be emptied only once for each rotation of the wheel.

Thus with the pocket capacity of the wheels about equal, as shown, the upper wheel will be capable of discharging a larger quantity than the lower, and consequently if the apparatus started from a stationary condition and was empty below the fluffer wheel and plates, the intermediate receiving chamber, 40, between the wheels 30, 50, 110 would quickly fill to the top.

After said chamber is thus filled, obviously the upper wheel cannot discharge more rapidly than the lower wheel takes away the material, and the result will be that the pockets in the upper wheel will not completely fill and empty as they pass the spaces in the fluffer plates, and the air displaced by the portion of material which falls from the pocket will only partially fill the pocket.

The fluffing effect will be such as has been described in connection with the description of the aerating of fluffing appliance, but only so much of the material will fall through the upper fluffer plate into the pocket as will serve to replace what has been discharged from it, and in so doing it will displace the air, which will have the desired churning and loosening effect upon the material entering from above, and the

material will be delivered from above the fluffer wheel and discharged into the chamber below, at the same rate that it is delivered from the chamber below by the feed wheel, the intermediate chamber remaining full of the light, fluffy, aerated material which does not become compressed by the material above the fluffer wheel in the supply hopper as would be the case if it were taken directly from the hopper by a feed mechanism of any usual kind.

It may be noted, furthermore, that the feed wheel has at the point where the buckets pass out from beneath the apron, 15 54, a similar loosening and aerating effect on the material entering the buckets, which must displace the air in them, so that the entering material and that somewhat above it will be more or less agitated, loosened, 20 and lightened by action of the air at this point.

While it is difficult to state just exactly what takes place in the aerating mechanism, it is probable that the pockets of the fluffer 25 wheel do not alternately completely fill and empty, but remain more or less filled with eddying air, with the particles suspended in the air and continually settling therefrom onto the accumulated material below 30 and entering from the more compact material above.

The pockets in the discharge wheel, while having to a limited extent the loosening, or aerating action of the fluffer wheel and 35 plates, travel a sufficient time in communication with the space above, while closed below, to become filled with the material at the density which it has when settling from a condition of suspension in the air.

40 The fluffer wheel and plates, or aerating devices, serve to prepare the material, or bring the more or less compact and lumpy powdered material to the condition in which its particles are separated and individually 45 suspended in the air, and, so far as their condition is concerned, suitable to be carried by an air current to the point of consumption.

With such preliminary treatment alone 50 it would be difficult, or practically impossible, to regulate closely the rate of feed, and consequently the prepared material is accumulated, or permitted to settle (except for the action of the distributor in the receiving chamber) and thus acquires a mass 55 of uniform density capable of being measured with a considerable degree of accuracy and delivered at any desired rate within wide limits by a corresponding regulation of 60 the speed of movement of the discharge wheel, without loss of the quality required for suspension in and uniform distribution throughout the conveying air current.

In the case of the preparing and feeding 65 appliances it is obviously immaterial,

except as a matter of mechanical convenience, which is the stationary and which the movable one of the relatively movable components.

The method of treating the material involved in the operations hereinbefore described is particularly intended and peculiarly adapted for the feeding of pulverized coal to furnaces employing such a fuel.

For best results such pulverized coal should be fed uniformly at any desired quantity rate, with the particles, which are minute, separated from one another so that when picked up and mixed with the air blast the result is in the nature of a cloud of fuel, with each coal particle individually suspended in and entirely surrounded by air for its combustion.

To accomplish this result in the operation hereinbefore described, the pulverized material, specifically coal, is advanced in mass by gravity to the apparatus, in which small portions of the coal are separated from the mass by permitting them to drop into the air trapped spaces or pocket chambers of the fluffer wheel, in which dropping they displace some of the air, and the displaced air is forced up through the separated portions entering the pockets so as to disintegrate such portions and separate the particles of pulverized fuel and bring them individually into suspension in the air, from which they are permitted to settle.

Fuel in this condition is suitable for delivery to the furnace or to the air blast by which it is conveyed to the furnace and for this purpose the lower feed wheel, above described, feeds consecutively small separated portions of the prepared and settled fuel to a point where they fall into and are picked up by the air blast and form therewith the desired uniform cloud-like mixture of air and minute particles of pulverized coal, each such separated portion being delivered gradually so that the consecutive delivery of the separated portions affords a substantially continuous delivery of the suspended coal particles, at any desired quantitative rate.

I claim:

1. The combination with a supply bin and duct for powdered material, of a preparing appliance comprising a pocketed wheel and recessed plates above and below the same, alternately covering and uncovering the said pockets at top and bottom as the wheel rotates; a receiving chamber below said wheel, and a pocketed discharge wheel at the lower end of said chamber and a closure for the lower ends of the pockets, except at one portion of their movement, said closure having a discharge port longer than the peripheral length of one of the pockets and narrower than the radial width of said pockets near one end and increasing to a

width substantially equal to the radial width of the pockets at the other end, and a closure above said wheel for the upper ends of said pockets while passing over said discharge port.

- 5 2. An apparatus for preparing and feeding pulverized fuel, comprising a supply receptacle for said fuel and a passage leading down therefrom; preparing means for 10 loosening the said material and placing its particles in suspension in the air; a receiving chamber in which the particles from the preparing appliance settle and accumulate at substantially uniform density; agitating 15 devices in the supply space above, and the receiving chamber below the preparing means; feeding or discharging means for delivering said material from the said receiving chamber; a duct through which the 20 powdered material falls; and an air duct with means for maintaining the flow of air therethrough substantially in proportion to the amount of powdered material delivered for receiving the material thus delivered and 25 conveying it in suspension to the point of consumption.
